UNITED STATES PATENT OFFICE.

KARL EGGAERT, OF ARBON, SWITZERLAND, ASSIGNOR TO THE FIRM OF ADOLPH SAURER, OF ARBON, SWITZERLAND.

APPARATUS FOR PRODUCING MACHINE-EMBROIDERY.

1,051,492.

Specification of Letters Patent. Patented Jan. 28, 1913.

Application filed July 10, 1911. Serial No. 637,753.

To all whom it may concern:

Be it known that I, KARL EGGAERT, a subject of the Emperor of Germany, residing at Arbon, Switzerland, have invented new and useful improvements in Apparatus for Producing Machine-Embroidery; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to an apparatus for producing machine embroidery.

The invention has for its object cooperating card punching and embroidering machines, wherein the card after having been punched by the punching machine operates the jacquard mechanism controlling the automatically moved embroidery frame of the embroidering machine; and the specific embodiment of this invention comprises first 20 punching a row or set of holes in the card and then causing said card to operate the said jacquard mechanism before the card or strip is fed to position for the punching of the next row or set of holes. There is a decided advantage in such a structure. It insures absolute certainty of the correctness of the punched card, because after each row or set of holes has been punched in the card, said holes immediately, and before the 25 punching of any other jacquard controlling holes, operate the embroidery frame of an automatic embroidering machine.

This machine produces a control embroidery which progresses with the punching, so that any errors are immediately detected in the embroidery reproduced from the card, and such errors can be immediately corrected. Consequently when the jacquard card is used in a separate embroidering machine and errors occur, it is certain that such errors are due to the derangement of the mechanism of the separate embroidering machine, or to other causes, and are not due to errors in the punching card.

30 Referring to the drawings, which illustrate by way of example one form of machine embodying my invention, and in which like parts are similarly designated— Figure 1, is an elevation, and Fig. 2 is a plan of such machine.

The automatic embroidery frame moving device 1 of the embroidering machine is contained in a casing 1^a. The blades or fingers 2 and 2^a of the jacquard apparatus for selectively controlling the movement of the 50 fabric frame 10 project from the casing 1^a. This jacquard mechanism has two operating shafts 20 and 21, each of which has a bevel pinion 18 operating bevel gear wheels and spur gears that mesh with racks 19. Each 55 of the racks 19 is independently movable, so that one of them transmits motion corresponding to one component and the other transmits motion corresponding to the other component of the rectangular components 70 of the movements of the frame 10, the same being transmitted to the embroidery frame by the cross 17.

The specific structure comprising the jacquard mechanism may be of any type, 75 provided its jacquard blades, fingers, needles or the equivalent, have ends projecting into a position operative for the purposes of this invention. The illustration of the embroidery frame and the jacquard mechanism is sufficient for the proper understanding of this invention by those skilled in the art.

The punching mechanism comprises two 80 punch-controlling pin drums 3^a and 3^b having concentric shafts provided with gear wheels 15^a and 15^b respectively. These gear wheels 15^a and 15^b respectively gear with racks 14^a and 14^b connected to suitable points of a pantograph 13 for producing rotation 85 of the pin drums 3^a and 3^b corresponding to the rectangular components of the movements of the tracer point of the pantograph. There are two sets of punches, 5^a and 5^b, each set corresponding to one of 90 the components of movement. The punches comprise rectilinear slides one end of each of which cooperates with a pin on one of the pin drums 3^a and 3^b, and the other end cooperates with a slotted die member 50 100 having a row of perforations 51 in alignment with the ends of the punches, and also in alignment with the ends of the jacquard fingers 2. The die member 50 has a slot 105 extending vertically through it, and forms part of a slide 8 slidable on guides λ to and from the punches 5^a and 5^b and the jacquard fingers 2 and 2^a. The movement of the die member and slide may be accomplished in 110 any suitable manner, but I have shown for

this purpose a shaft *a* mechanically driven from any suitable source of power. This shaft carries at each side of the slide 8 a disk 16 provided with a cam groove *b*.
5 There are two levers *d*, one on each side of the machine, pivoted at *e* and whose lower ends carry rollers *c* that enter the cam grooves *b*. The upper ends of the levers *d* have pins *g* that engage the opposite ends of
10 the slide 8.
The jacquard card 6 is guided through slot in die member 50 over a roll 7 to a suitable take-up drum 21; and the jacquard card 6 is intermittently moved in the direction of the arrow Fig. 1. At every period of rest of the card the cams 16 move levers *d* which first moves the die member 50 with the jacquard card 6 against the punches 5^a and 5^b, thereby moving the punches toward
15 20 the pin drums 3^a and 3^b. Those punches which by reason of the previous selective positioning of the pin drums 3^a and 3^b by the pantograph have the pins of said drums in alinement therewith will be stopped by
25 30 said pins and punch the card. Those punches that are not stopped by pins are free to move farther toward the drums and do not perforate the card. The further rotation of shaft *a* and disks 16 moves slide 8 in the opposite direction away from the punches and the card is moved into contact with the fingers 2 of the jacquard mechanism. The ends of those fingers 2 that lie opposite the perforations in the card pass through them, and the ends of those fingers that do not lie opposite perforations in the card are operated by said card. After the jacquard fingers have been operated, the slide and card are moved to initial position and the card is
35 40 45 progressed through the slot in the die to present a new portion for perforation, meanwhile the pantograph 13 has been operated in accordance with the next stitch to position the pin drums 3^a and 3^b preparatory to punching the holes for the movement of the embroidery frame for said stitch.

I claim—

1. The combination with a jacquard-controlled embroidering machine and its jacquard mechanism; of a jacquard card 50 punching machine including punches, a movable guide for the card during the punching operation arranged in operative relation to both the punches and the jacquard mechanism for causing the punching of the card and causing the punched card to operate on said jacquard mechanism.

2. The combination with the fingers of a jacquard mechanism and the punches of a jacquard card punching machine; of a jacquard card guide between said fingers and punches, and means to move the guide first toward the punches for punching the card and then toward the fingers to cause the card to operate the fingers.

3. The combination with means to feed a jacquard card step-by-step, the fingers of a jacquard mechanism, and the punches of a jacquard card punching machine arranged in alinement with said fingers; of a combined die-member and guide for said card arranged between said fingers and punches and means to move the guide first toward the punches to punch the card and then toward the fingers to cause the card to selectively actuate them, said movements occurring between the feeding steps of the card.

4. The combination with a jacquard-controlled embroidering machine and its jacquard mechanism, of a jacquard card-punching machine including punches and means for holding a jacquard card, first for being operated upon by the punch, and then for the operation of the jacquard mechanism of the embroidering machine.

In testimony that I claim the foregoing as my invention, I have signed my name in presence of two subscribing witnesses.

KARL EGGART.
